EXPANSION BIT

Markworth Albert Shaw, Vancouver, British Columbia, Canada

Application May 3, 1941, Serial No. 391,739

1 Claim. (Cl. 145—124)

My invention relates to improvements in expansion bits, which are particularly adapted for drilling tapered holes in lumber in which dowels and the like are to be secured by fox wedging.

The object of the invention is to provide means whereby the holes drilled increase in diameter progressively from the surface of the material drilled to the bottom of the hole. A further object is to provide a structure wherein the cutting elements are so supported in the drill stock as to prevent chattering, to the end that the walls of the hole are smooth and the grain of the wood free from ragged appearance.

The invention consists of a drill stock in which a pair of cutting elements hingedly connected together at one end are mounted and in which means are provided for moving the cutting elements endwise beyond the end of the stock and for spreading the projecting ends of said elements apart, as will be more fully described in the following specification and shown in the accompanying drawing, in which—

Figure 1 is an elevational view of the invention with the cutting elements retracted.

Figure 2 is a part sectional view showing the cutting elements extended.

In the drawing like characters of reference indicate corresponding parts in each figure.

The numeral 1 indicates a drill bit stock which is adapted to be held in a chuck of a drilling machine. The stock 1 is slotted upwardly from its lower extremity as at 2 to receive a pair of cutting elements 3. Each of the cutting elements is an elongated strip of steel having a substantially V-shaped outer end 4, one angle of the V being bevelled off and suitably curved in the direction of rotation to provide a cutting edge 5. Each cutting element is provided intermediate its length with an arcuate slot 6 which extends from about the longitudinal axis of the strip downwardly and outwardly towards the cutting edge 5. One side of each cutting element is curved as at 7 to prevent binding in the hole bored.

Extending through the stock 1 and the arcuate slots 6 of the cutting elements is a pin 8. An elongated slot 10 is formed intermediate the length of the stock 1 which is transverse to the slot 2 and a pivot pin 12 extends through said slot and the upper ends of the cutting elements 3. The length of the pivot pin 12 is such as to project into an annular groove 13 which is formed in a collar 15. The collar 15 is made in any suitable manner to slide freely upon the stock 1 and permit the stock to rotate therein, it is provided with trunnions 16 on its periphery which are adapted to be engaged by a suitable feed lever, fulcrummed on a stationary part of the drilling machine.

In operation, the bit is brought down approximately to the face of the work to be drilled and the machine is set in motion. The collar 15 on being lowered along the stock forces the pivot pin 12 and the cutting elements 3 downwardly to project beyond the lower end of the slot 2. The outer ends 4 of the cutting elements are progressively spread apart as the elements descend due to the curvature of the arcuate slots 6 as their side edges ride downwardly on the pin 8.

What I claim as my invention is:

An expanding bit comprising a stock having a slot extending from its lower end inwardly, a pair of cutting elements normally housed within the slot and extending therebelow, said elements each having a cutting edge equal to the width of the stock and said elements being pivotally connected adjacent one end by a pivot pin, said stock having a longitudinal slot transverse to the first named slot through which the pivot pin extends, means engaging the pivot pin externally of the stock for moving said cutting elements to project downwardly beyond the lower end of the stock, and means for guiding the lower ends of the cutting elements outwardly as they are moved downwardly.

MARKWORTH ALBERT SHAW.
